UNITED STATES PATENT OFFICE.

RANDALL MCFARLAN, OF CINCINNATI, OHIO, ASSIGNOR TO THE WM. POWELL CO., OF CINCINNATI, OHIO, A CORPORATION OF OHIO.

AIR GUN AND THE METHOD OF MAKING IT.

Application filed June 11, 1924. Serial No. 719,438.

My invention relates to air guns and particularly to devices of this character adapted for use in cleaning sand molds, core boxes, flasks, patterns, automobiles, armatures and fields, switch boards, controllers, types, electros, wood-cuts, monotypes, newspaper machinery and for blowing chips, borings, filings, etc., from machinery, and for various other similar blowing and cleaning operations.

The objects of my invention are to provide an air gun having few parts and arranged so as to avoid disarrangement thereof by inexperienced operators; to provide a press button adapted when manually operated to open the air passage through said gun and having a shank attached thereto adapted to automatically close said air passage, when pressure is released from said button, caused by the pressure of the air within the air gun and irrespective of the aid of resilient means; to provide an air gun adapted, when laid down, to automatically take a position relative to said press button, whereby said press button is adapted to disengage contact with the surface upon which the gun rests, thereby permitting the valve within the gun to have freedom to automatically close the air passage; and to provide an air gun having an arrangement and combination of parts adapted to enable said gun to be produced at a low cost of manufacture.

My invention consists in providing a body portion having two flat sides oppositely disposed and extending in parallel relation to the valve stem, said body having a transverse hole therethrough in parallel relation with said flat sides and having a longitudinal hole leading from the nozzle to said transverse hole, and having a hole leading from the air supply connection socket diagonally to said transverse hole whereby an air passage is formed through said gun by way of said diagonal transverse and longitudinal holes; in providing a valve stem or shank having a reduced section and slidably mounted within said transverse hole and a press button fixed to the outer end of said shank as by a burnishing or peening process; in providing said press button with means adapted to prevent escape of air from said gun when said button is pressed inwardly; in providing said transverse hole with an enlarged cylindrical chamber and a valve seat formed adjacent the inner end of said chamber; in providing a valve on

said stem having tapered sides adapted to seat in said valve seat for cutting off the flow of air through said gun; in providing a part of said chamber with internal threads adapted to receive an externally threaded plug; and in providing said body with means adapted to protect said press button against accidental inward pressure when said body is laid down.

My invention also consists in the combination and arrangement of parts and in the details of construction as herein set forth and claimed.

In the drawings:

Fig. 1 is a side elevation of my invention;

Fig. 2 is a front end view;

Fig. 3 is a section corresponding to 3—3 in Fig. 5;

Fig. 4 is a section taken on a line corresponding to 4—4 of Fig. 3;

Fig. 5 is a plan view;

Fig. 6 is a bottom view;

Fig. 7 is a section of my press button;

Fig. 8 is a side elevation of the valve and valve stem or shank;

Fig. 9 is a perspective view showing my invention in modified form having an outwardly extending flange adjacent the press button; and

Fig. 10 is a side elevation of the same.

In the embodiment of my invention as illustrated and which shows a preferred construction, I provide body 1 having transverse cylindrical hole 2 therein and leading into enlarged transverse chamber 3 having internal threads 4 formed therearound at its outer end 90 for receiving screw 5 adapted to plug the outer end 6 of chamber 3 against air leakage. The edge of shoulder 7 formed by transverse hole 2 leading into enlarged transverse chamber 3 is beveled at 8 thereby forming a seat 95 for tapered valve 9. Valve 9 is integral with valve stem or shank 11 having enlarged cylindrical section 12 and slidably mounted in transverse hole 2. Shank 11 has press button 13 fixed to its outer end 14 by any suitable means, preferably consisting in providing the press button with a centrally disposed hole 15 having flared sides 16 at its outer end and adapted to receive end 14 of shank 11, having longitudinal recess 17 therein thereby permitting the metal shell of the shank adjacent recess 17 to be flared outwardly in engagement with flared sides 16 of press button 13 by a usual burnishing process whereby the press button is securely fixed to shank 11.

The inner portion 18 of press button 13 is beveled and fitted in valve seat 19 of body 1 for the purpose of preventing escape of air through the outer end of transverse hole 2, when the air gun is in operation.

The inner end 20 of body 1 has threaded socket 21 therein and extending longitudinally thereof for forming connecting means with the external threaded end of the usual 10 air supply pipe or hose. Cylindrical hole 22 leads diagonally from socket 21 to chamber 3, and may be conveniently drilled by inserting the drill in socket 21.

Longitudinal cylindrical hole 23 leads from 15 transverse hole 2 adjacent reduced portion 24 of shank 11 to internally threaded hole 25 in the outer end 26 of body 1. Suitably formed nozzle 27 has integral end 28 threaded in hole 25 of body 1 and has air outlet 29 leading from 20 longitudinal hole 23 to nose 30 of the nozzle.

In Figs. 9 and 10 I show a modified form 25 of my invention having outwardly extending transversely curved flange 32 adjacent the front of press button 13. The flange is for the purpose of preventing accidental pressure 30 of the press button when the air gun is laid down, and is slightly curved, transversely, to conform to the shape of the end of a thumb usually employed to exert inward pressure on the press button.

As shown in Fig. 3, I provide the inner end 35 of valve stem 11 with a screwdriver slot in order that when screw plug 5 is removed a screwdriver may be inserted whereby the valve stem 11 may be rotated for the purpose of grinding the tapered valve 9 and its adjacent seat.

The operation of the mechanism of my device is as follows:

40 A usual compressed air supply pipe is received by threaded socket 21 in end 20 of body 1 for the purpose of admitting compressed air into chamber 3 through diagonal hole 22, whereby valve 9 is forced upwardly engaging 45 inclined sides 10 with valve seat 8 thereby preventing air from flowing into transverse hole 2.

When it is desired to admit compressed air 50 from chamber 3 through the valve and into transverse hole 2, longitudinal hole 23, and through nozzle outlet 29, manually operated press button 13 is pressed inwardly, thereby 55 disengaging inclined sides 10 of valve 9 from valve seat 8 whereby compressed air is permitted to flow from chamber 3 and through nozzle outlet 29 by way of transverse hole 2 and longitudinal hole 23. Enlarged part 12 of shank 11 is fitted in transverse hole 2 and inclined surface 18 of press button 13 fits in 60 valve seat or countersink 19, thereby preventing escape of air from the gun through the outer end of transverse hole 2 adjacent the press button.

Thus it is seen that I have invented an ex-

ceedingly simple, effective and efficient air gun having a two piece valve stem adapted to automatically close when hand pressure is released from press button 11, (forming one part of the stem) and having no complicated parts adapted to get out of order.

Great economy is effected by my construction both by way of materially reducing the cost of repairs and upkeep in comparison to usual air guns employing springs or other complicated valve mechanisms. I also provide a body portion 1 adapted to be molded by a usual metal casting process, then drilling and threading holes 3, 21 and 23, and drilling transverse holes 2 and diagonal hole 22, and beveling valve seats 8 and 19 which completes the mechanical work required to produce the finished body. Other parts such as press button 13, valve shank 11, screw 5 and nozzle 27 may be made by use of automatic machines in large quantities, thereby rendering an efficient and sturdy construction at a low cost of manufacture.

I also construct the body 1 with comparatively narrow edges 31 and flat sides 33 so that when the gun is laid upon a flat surface it will automatically rest upon one of its flat sides out of contact with press button 13, thus avoiding accidental pressure when the gun is laid upon a flat surface and permitting the valve freedom of action in closing thereby conserving the supply of compressed air.

While I have shown and described a particular construction of mechanism it will be understood that it may be varied in construction and arrangement without departing from the scope or spirit thereof, as defined in the claims, as for instance, the flange or projection 32 may extend either partly or entirely around and above the press button.

What I claim as new and desire to secure by Letters Patent is:

In a self-closing blow gun, a body having a drilled transverse hole part way therethrough, a countersink at the outer end thereof, an enlarged chamber extending from the inner end of said hole to the outer part of said body and in alignment with said hole and having internal screw threads therein, a screw plug in the outer end of said chamber having a recess therein, a solid valve stem slidably mounted in said hole and having a reduced intermediate section to permit the free passage of air therearound within said transverse hole, a press button fixed to the outer end of said valve stem, means for sealing the outer end of the transverse hole to prevent leakage of air around the valve stem when the valve is open, a tapered valve seat formed at the junction of said hole and said chamber, and a tapered valve on the inner end of said valve stem adapted to seat on said tapered valve seat.
